BOTTLE OPENER WITH SPRAY GUARD

Herbert Nash Lapetina and Arthur Eugene Hall,
Norfolk, Va.

Application September 15, 1949, Serial No. 115,902

1 Claim. (Cl. 81—3.1)

1

This invention relates to bottle openers such as used for soft drinks and beer bottles and in particular includes a guard positioned over a bottle opener and having a sponge rubber block therein with a slot through which the neck of a bottle is extended when it is desired to remove a cap from the bottle.

The purpose of this invention is to provide means for arresting the leakage or small spray discharged from the upper edge of a bottle cap as the cap is removed from a bottle to eliminate the usual unsanitary condition around bottle openers.

To make bottle openers sanitary box-like housings with openings for receiving necks of bottles have been provided around the openers but the spray discharged from the upper edge of a bottle cap as it is started away from the end of a bottle, whereby the pressure in the bottle is released, produces a sticky film around the opening in the casing so that unsanitary conditions continue to exist with the usual type of bottle openers. With this thought in mind this invention contemplates a comparatively soft washer mounted against the inner surface of the bottle neck receiving opening of a casing surrounding a bottle opener wherein the neck of a bottle is inserted in a slot in the washer and with the washer fitting snugly around the bottle neck the spray of fluid escaping around a bottle cap is deflected downwardly.

The object of this invention is, therefore, to provide means for mounting a spray arresting washer or block against the inner surface of a box like casing positioned over a bottle opener whereby it is necessary to insert the neck of the bottle in a slot therein in order to reach the bottle opener.

Another object of the invention is to provide a spray arresting device for bottle openers that may be installed on bottle openers now in use.

A further object of the invention is to provide a shield having a slot therein and means for mounting the shield in relation to a bottle opener so that the shield receives a small spray that may be discharged from a bottle when the crown or cap of the bottle is removed, which is of a simple and economical construction.

With these and other objects and advantages in view the invention embodies a block of soft resilient material having a slot extended upwardly therein from the lower end and means for mounting the block in a position spaced from a bottle opener whereby the neck of a bottle from which a cap or crown is being removed

is inserted in the slot as the cap is pried therefrom.

Other advantages of the invention will appear from the following description taken in connection with the drawings wherein:

Figure 1 is a front elevational view showing a block of resilient material secured by an outer frame on a casing which is positioned over a bottle opener.

10 Figure 2 is a vertical section through the casing and block of resilient material being taken on line 2—2 of Figure 1.

Figure 3 is a detail showing a blank from which the outer frame by which the block is secured 15 to the face of the casing is formed.

Figure 4 is a detail showing an inner mounting element in the upper end of which the block of resilient material is positioned and through which the block is mounted in the casing.

20 Figure 5 is a detail illustrating the block of resilient material with a keyhole slot therein.

Referring now to the drawings wherein like reference characters denote corresponding parts the sanitary device for bottle openers of this invention includes a block 10 of sponge rubber or other comparatively soft resilient material, a mounting element 11, and a frame 12. The block, mounting element and frame are mounted on an outer wall 13 of a boxlike casing 14 that may be positioned over a bottle opener, which is indicated by the dot and dash lines 15.

In the design shown the block 10 is formed with an arcuate upper surface 16 and a flat base 17, and a keyhole slot having a cylindrical inner part 18 with an outwardly flared connecting channel 19 is positioned in the center of the block with the channel 19 opening through the base 17 and with the upper end thereof communicating with the slot 18. This block is 35 formed of sponge rubber or other suitable resilient material, and in assembling the parts the block is inserted in a recess 20 in the inner section of the element 11 with the web or intermediate portion of the block extended inwardly as

40 shown in Fig. 1. The element 11 with the block 10 positioned in the recess 20 therein is secured against the inner surface of the front wall 13 of the casing 14 by prongs 21 that extend through slots 22 in the wall 13. The block and 45 mounting element are secured in position by similar prongs 23 extended from the inner edge of the frame 12, and which extend through the material of the block and over the inner edge of the element 11 as shown in Figure 2.

With the parts arranged in this manner the

neck of a bottle is inserted through the slot in the box like casing to reach the bottle opener 15 and with the neck of the bottle in this position the soft sponge rubber block closes the area over the neck of the bottle and arrests the spray discharged as the bottle crown or cap is started away from the end of the bottle. The block of resilient material may be removed and replaced as desired.

The size and shape of the block of resilient material and also the design of the surrounding housing may be modified as desired and it will be understood that other modifications may be made in the design and arrangement of the parts without departing from the spirit of the invention.

What is claimed is:

The combination of a box like casing having a front wall and side and end walls extended therefrom, and a bottle cap remover, with a fluid deflecting shield, said casing positioned over the bottle cap remover and having a centrally positioned elongated vertically disposed slot in the front wall, said slot being aligned with the bottle cap remover whereby it is positioned to receive the neck of a bottle having a cap thereon

10
15

with the cap extended into said bottle cap remover, an elongated mounting element having a recess in the upper part thereof extended around the slot in the front wall of the casing and positioned against the inner surface of said front wall, and a U-shaped block of resilient material extended over the upper end of said elongated slot in the front wall of the casing and positioned in said recess of the mounting element, and means mounting said mounting element and fluid deflecting shield on the inner surface of the front wall of the casing with said shield positioned whereby fluid being sprayed outwardly around a bottle cap positioned in the bottle cap remover is deflected downwardly thereby.
